Primary Examiner — Deanna L Pratt(74) *Attorney, Agent, or Firm* — Lerner, David, Littengerg, Krumholz & Mentlik, LLP(57) **CLAIM**

The ornamental design for a display screen or portion thereof with graphical user interface, as shown and described.

DESCRIPTION

FIG. 1 is a front view of an image of a display screen or portion thereof with graphical user interface according to an embodiment thereof.

The broken line showings of portions of a display screen, text, and other features in the figures are environmental only and form no part of the claimed design.
